FRÉDÉRIC MANGE, OF PARIS, FRANCE.

MATCH-STICK-CONVEYING APPARATUS FOR USE IN CONNECTION WITH THE
MANUFACTURE OF MATCHES.

Application filed June 29, 1925, Serial No. 40,462, and in Switzerland July 10, 1924.

In the manufacture of matches, hitherto the match sticks have usually been piled loosely, but all lying in the same direction in a magazine. From this position the sticks are pushed out longitudinally into the containers of the impregnating frames by means of thin plungers or pins which act on the ends of the individual sticks. With this method of pushing the sticks out, various faults very often occur. Owing to the loose piling of the sticks the plunger often misses so that the impregnating frames are not completely filled, which gives an uneconomical working of the apparatus. Further, by the action of the plunger on their ends, the sticks are split or damaged which results in a considerable reduction in the quality of matches. Also there is a loss in all impregnating devices which have passages or channels, etc. of fixed cross-section, because no sticks of insufficient cross-section can be held therein.

The object of the present invention is to avoid these difficulties and to provide an apparatus of feeding which allows the individual match sticks to be conveyed without damage and waste, to the operating positions for the manufacture of matches so that a complete use is made of all the sticks supplied by a cutting machine. By the present invention all difficulties which are caused by the individual holding of the match sticks owing to the working methods employed, are avoided whether for example, used in the so-called complete machines or in the machines for feeding the impregnating frames of the known Seebold type and the like.

According to the present invention individual match sticks, preferably separated individually from a formation in series, are held in individual clips at right angles to their length, which allows of the sticks being gripped and firmly secured crosswise to their length, and these clips are arranged in rows and so controlled as to convey the match sticks to the various operating positions used in the manufacture of matches. Owing to the arrangement in series of the sticks it is preferable to provide groups of individual clips on carrying bars so that

each of the groups of clips can be simultaneously filled with match sticks which gives a satisfactory yield to the apparatus.

The improved apparatus has the feature that the separate individual clips are conveyed to a match stick magazine of the series type and by a relative sliding movement at right angles to the length of the sticks arranged in adjacent rows in the magazine they can grip the sticks across the length thereof, after which they are conveyed together with the sticks held therein to the various working places.

The drawing illustrates a construction of the apparatus according to the invention.

Figure 1 shows in side view a portion of the apparatus from the position of feeding the sticks out of the magazine to the position where the clip carrying bars are transferred to a chain which passes over the positions where the treating materials are applied to the match sticks.

Figure 2 is a plan view thereof.

Figure 3 shows in side view partly in section the arrangement of rollers for applying the materials.

Figures 4 to 7 illustrate details of a method of construction of the magazine and of the clip carrying bars for the match sticks, Figures 4 and 5 being a side elevation and a plan view of a part of said magazine, whilst Figures 6 and 7 show the clips in side elevation and plan view.

A magazine 1 (Figures 1 and 2), in which the sticks from a cutting machine are arranged in series in separate compartments, is supported at the filling place opposite a double track conveying chain 2 in such a way that the stick rows in the magazine are directed at right angles to a downwardly moving portion of the chain 2. The rows of sticks are held in the magazine 1 by springy or resilient partitions 3 as shown in Figures 4 and 5. At the delivery ends these partitions 3 are cut out at 4 in the manner shown in Figure 6 in such a way that the individual sticks can be gripped across their length. The sticks are taken out of the magazine by means of a number of separate clip carrying bars 5 which take the front stick from

each row of sticks in the magazine and for this purpose are provided with a number of individual projecting clips 6 corresponding to the number of the magazine compartments.

The clips of the carrying bars 5 each consist of a pair of spring tongues 6^a (Figure 7) which are bent inwards behind their open ends to form an abutment so that the said clips 6 can only pick up and grip one stick at a time. The sticks are gripped over a considerable part of their length and are thus held safely. Owing to their elasticity the clips can pick up sticks of varying thicknesses.

The carrier bars 5 are held on the double track conveying chain 2 by their ends each between a fixed jaw 8 and a spring pressed pivoted jaw 9 and are moved inwards and pressed against the magazine at the filling place by a movable abutment 10 between the chain tracks, which is allowed by the slack running of the conveying chain 2 without difficulty, the fingers 10^a serving as a stop and so pressing back the ends of the sticks that their entry into the clips 6 is limited. The movement of this abutment 10 is effected by a rotatable eccentric cam 11, which receives its movement through the chain drive 12 from the main shaft 13 (Figure 1). The shaft 13 is driven through a gear 14 by an electric motor 15.

The front stick of each series of the magazine is pushed out of the magazine compartments into the corresponding clip of the waiting carrying bar 5 by the action of ejecting plungers 16, which are arranged on a slide 17 and pass from behind into the magazine compartments. This slide 17 is urged towards the chain 2 by a steel tension band 18 with a weight 19. The steel band 18 is fastened to rollers 20, 21, and to the projection 17^a of the slide 17. By the co-operation in opposite directions of the plungers 16 entering the magazine compartments and the abutment 10 acting on the chain 2, the former under the influence of the weight loaded steel band 18 and the latter under the action of the eccentric cam 11, the front sticks of the magazine are pressed out of their compartments into the spring clips 6 of the waiting carrying bar 5, the pressure of the plungers acting at right angles to the axes of the sticks and over their whole length and there being always only room for one stick in the spring clips.

After the passage of the sticks into their clips and before the abutment 10 is moved back by the action of the eccentric cam 11, the pressure of the magazine is released by the following mechanism. One of the supporting rollers 20 of the steel band 18 is constructed with a slideable and rotatable 65 conical clutch member 25 (Figure 1). This

clutch member can be pressed into a conical recess in the roller 20 by means of a spring pressed forked lever 26 which co-operates with a rotatable cam 27, which is driven through a chain drive 28 from the main shaft 13. When this has occurred, that is when the cam 27 allows the lever 26 to be acted on by the tension of its spring 26^a, another cam 30 combined with and following the cam 27 acts on a spring pressed push rod 31, which is linked to a pin 32 of the clutch member 25, and lifts this push rod 31 somewhat to thus effect a slight rotation of the clutch member 25 and the roller 20 engaged therewith in the direction and 70 to the extent that the pressure of the plungers 16 on the chain 2 is released (against the action of the weight 19). After this the abutment 10 is moved back and the chain 2, which is driven by means of the wheel 35 (Figure 2), is moved on another step by the action of a Maltese cross mechanism, whose crank pin cam 36 is situated on the main shaft 13 and whose Maltese cross disc 37 on the shaft of the 75 wheel 35, so that a new clip carrying bar 5 is moved on into the waiting position. In this way the bars 5 in the conveying chain 2 are successively loaded each with a series of sticks and are moved on intermittently from the filling place. During their passage through the machine the loaded bars 5 reach a cross-wise transfer place A. Here the pivoted jaws 9 are opened by an abutment 40 (against the action of their springs) 80 to release the carrying bars 5, whilst a double track cross-wise chain 41, which runs over the chain wheels 42, 43, and is provided on each track line with carrier thumbs 44, through the latter takes the released clip carrying bar 5 with it and slides the same along a track 45 and finally delivers it to another double track chain 50, which, like the chain 2, is provided with a series of holding jaws 58, 59, for the clip carrying bars, and on its horizontal course, in the manner shown in Figure 3, carries the bars 5 with the downwardly projecting match sticks over the devices for applying the combustible substance and kindling materials. The opening of the jaws 58, 59, at the picking up place is effected as before by the action of an abutment 51 which acts on a tail of the movable jaws 59, whilst the closing of the jaws is effected by their own springs. 90 Here, as before at 9^a, the movable jaws 59 have a projecting claw 59^a for security in holding the clip carrying bars.

The device for applying the combustible substance comprises a stationary trough 60 (Figure 3) for containing this substance in a fluid state (which is for example melted paraffin or fluid sulphur), and a roller 61 in this fluid material. The roller rotates in 95 synchronism with the movement of the chain 100

56, which roller is provided on its periphery with a series of longitudinal small dipping troughs 62, whose distance apart in the peripheral direction corresponds to the distance apart of the clip carrying bars in the

5 distance apart of the clip carrying bars in the said chain 50 and in the axial direction according to the distance apart of the clips on the said bars. During the intermittent movement of the chain 50 and the correspondingly intermittent rotation of the roller 61 the match sticks are dipped to the desired depth along the top line of the roller 61 into the dipping troughs 62, which troughs are filled with the combustible substance by the rotation of the roller. The depth of dipping can be easily regulated as the roller 61 is supported on a double lever 64 which can be positioned by a micrometer screw 63, so that by turning this screw the 10 height of the roller can be adjusted according to the length or thickness of the sticks without making any alterations in the path of the loaded bars. Naturally this adjustment in height of the roller can 15 be effected without altering its drive.

After the application of the combustible substance the thus impregnated sticks in the bars pass over a heating device 66, and then pass over the device for applying the kindling material. The latter also comprises a stationary trough 70 for containing this material in a fluid state and a roller 71 rotating therein, which in this case, however, owing to the thickness or viscosity of the kindling fluid in the trough 70, is provided with peripheral grooves 72, in which the sticks by dipping into the kindling material in the grooves receive their striking heads. In this case also the roller 71 is adjustable in height 20 by means of the supporting lever 74 provided with a micrometer screw 73 for the purpose of easy adjustment of the length of the match head.

After the impregnated sticks or matches 25 have been passed over a heating device 75 they are conveyed by the chain 50 to a delivery place not illustrated, which can be varied according to the requirements of the factory, where they are released from the 30 clip carrying bars and can be filled into boxes, preferably by means of a comb the teeth of which are engaged into the clips behind the sticks therein. The path to this delivery place can also serve as a drying 35 channel for the match heads. After this the clip bars return empty, to be delivered by a cross-wise conveying chain 80 (Figure 1) in a similar way to that described above, to the crossing part of transport chain 2, which 40 returns them to the magazine at the filling place.

In this manner the bars are loaded in a continuous progression with match sticks, and the sticks are supplied on their passage 45 with combustible substance and kindling ma-

terials, the bars then being emptied and after being returned to the filling place are loaded again with match sticks.

What I claim is:—

1. A match stick conveying apparatus for use in connection with the manufacture of matches, comprising a match stick magazine to hold the match sticks in upright position, spring clips to grip and hold each a match stick, means to produce a relative movement 75 between the match sticks in said magazine and the said spring clips transversely to the longitudinal direction of the match sticks to cause the same to enter crosswise into the spring clips, and automatic means to transfer the spring clips thus loaded to various working places for finishing matches.

2. A match stick conveying apparatus for use in connection with the manufacture of matches, comprising a match stick magazine 80 with compartments to hold the match sticks in upright position by parallel rows, spring clips arranged by series to grip and hold each a match stick, means to produce a relative movement between the match stick rows 85 in said magazine and the spring clip series transversely to the longitudinal direction of the match sticks to cause the same to enter crosswise into the spring clips, and automatic means to transfer the spring clips thus loaded to various working places for finishing matches.

3. A match stick conveying apparatus for use in connection with the manufacture of matches, comprising a match stick magazine 95 to hold the match sticks in upright position, spring clips to grip and hold each a match stick, means to approach the spring clips to said magazine transversely to the longitudinal direction of the match sticks so as to slide same crosswise over the match sticks, and automatic means to transfer the spring clips thus loaded to various working places for finishing matches.

4. A match stick conveying apparatus for use in connection with the manufacture of matches, comprising a match stick magazine 100 with compartments to hold the match sticks in upright position by parallel rows, spring clips to grip and hold each a match stick, conveying bars to carry said spring clips side by side according to the relative distance between said magazine compartments, means to carry and move the clip carrying bars towards said magazine transversely to the longitudinal direction of the match sticks 105 so as to slide their clips over the match sticks therein across their longitudinal direction, and automatic means to transfer the clip carrying bars thus loaded to various working places for finishing matches.

5. A match stick conveying apparatus for use in connection with the manufacture of matches, comprising a match stick magazine 110 to hold the match sticks in upright position,

spring clips to grip and hold each a match stick, said spring clips having springy side walls with a flared mouth and with stop means to allow gripping of only one single match stick, means to produce a relative movement between the match sticks in said magazine and the said spring clips transversely to the longitudinal direction of the

match sticks so as to cause same to receive and grip match sticks across their length, and automatic means to transfer the spring clips thus loaded to various working places for finishing matches. 10

In witness whereof I have hereunto signed my name this 17th day of June 1925.

FRÉDÉRIC MANGE.
